UNITED STATES PATENT OFFICE.

JOHN H. FRINK, OF DETROIT, MICHIGAN.

DUPLICATE MEMORANDUM OR SALES SLIP.

SPECIFICATION forming part of Letters Patent No. 288,048, dated November 6, 1883.

Application filed January 12, 1883. (Model.)

To all whom it may concern:

Be it known that I, JOHN H. FRINK, of Detroit, county of Wayne, State of Michigan, have invented a new and useful Improvement 5 in Duplicate Memorandum or Sales Slips; and I declare the following to be a full, clear, and exact description of the invention, such as will enable others skilled in the art to which it pertains to make and use it, reference being had 10 to the accompanying drawings, which form a part of this specification.

My invention consists in the combination of devices and appliances hereinafter specified, and more particularly pointed out in the 15 claims.

In the drawings, Figure 1 is a perspective view, and Fig. 2 a side elevation, of a device embodying my invention.

My invention has for its object the construction of a book or block of paper for use by merchants and others where it is desirable to have all memoranda made in duplicate, both being capable of ready removal—as, for instance, one for the cashier and one for the customer.

A represents the ordinary cover, adapted for use with the blocks.

A' is an end piece or fly for securing the block in place by a rubber band or equivalent, A².

B represents the paper leaves, perforated along the two lines b and b'. These leaves are all blocked and united at B', and upon the top is a carbon sheet, either blocked onto said leaves, 35 or laid upon the same, and held in place by the end piece, A', and rubber A², with or without a thin paper covering or protection, B³. This carbon sheet and its covering are both made permanent with a block of paper, so as al-

ways to be ready and in place. To employ this feature of the device it is simply necessary to pass the head of the block B' beneath the fly A'.

Now, when a memorandum—as, for instance, of goods sold—is to be made, the lower 45 or free end of the top leaf is folded over on the line b onto the carbon sheet, as shown in Fig. 2. The memorandum is then made with a lead pencil in the usual manner, and the copy is formed on the underneath portion of the

50 same sheet. Both pieces are then ripped off along the perforated lines b and b', and the carbon sheet is left in proper position for the next memorandum.

It is apparent that neither the carbon sheet nor the memorandum-sheets can become displaced by severing the leaves from the stub at the head of the block, and when the block has been used up a new one can be inserted in the cover A. This construction obviates the necessity of a separate fly on the cover for holding the carbon paper, and also overcomes effectually the liability of deranging the remaining sheets by drawing out, as heretofore.

The slips of paper may or may not be printed in the form of a blank to be filled out, and 65 may be numbered as desired. This is applicable as well to telegraph-blanks, shipping-blanks, &c., as to salesmen's blanks, and I would have it understood that my invention contemplates its use for such purposes.

C is a memorandum-leaf upon which the clerk may keep account of his sales. I prefer to hold this leaf in place, as shown, by means of flies A³ and A⁴, attached to the cover, and constructed to fold over the ends of the leaf, 75 and adapted to be secured in place by rubbers or equivalents a and a'. This construction holds the leaf in place securely.

It will be seen from the foregoing that all the fly-leaves of the sheets—that is, the free 80 ends of the sheets from the line of perforations b outward—lie in contact with each other, and that the flexible leather back extends the full length of the sheets, including the fly-leaves, and hence the entire batch of leaves, with the 85 flexible leather back, can be folded at the middle of their length, thereby covering and protecting the sheets, and also the line of perforations b, so that the paper at this point will not become worn, torn, or soiled when carrying 90 the book in the pocket.

It will be obvious that the carbon sheet is always in proper position to produce the copies without having to manipulate or adjust the same every time one sheet and its fly-leaf 95 are removed, as heretofore in this class of books, it only being necessary in my invention to fold the fly-leaves of the sheets over upon the carbon sheet. Further, all the fly-leaves fold over together upon the carbon sheet 100 when it is desired to carry the book in the pocket.

What I claim is—

1. A memorandum-book for salesmen, composed of the flexible back-piece A, the series 105 of paper sheets provided with the lines of per-

forations b b' , and having one end secured to one end of the back, with the carbon sheet on top, the fly-leaves of the sheets from the line of perforations b outward all lying in contact 5 with each other, and all adapted to fold over the carbon sheet with one end of the flexible back, substantially as and for the purpose described.

2. A memorandum-book consisting of the 10 series of sheets provided with the lines of perforations b b' and a carbon sheet on top, and a flexible back extending the full length of the sheets and having one end turned around in the form of a fly, A' , which is confined down 15 upon the paper and carbon sheets by an elastic band, the fly-leaves of the sheets from the line of perforations b outward all resting directly against each other, and with one end of the flexible back adapted to fold over the carbon leaf, substantially as described.

3. The combination, with a block of memorandum-paper perforated along the lines b and

b' , of a cover, A , provided with a retaining-fly, A' , a carbon sheet secured with the memorandum-paper under the retaining-fly, said cover 25 also provided with flies A^3 and A^4 , adapted to secure the memorandum-leaf C in place, substantially as described.

4. The combination, with a block of memorandum-paper perforated along the lines b and 30 b' , of a cover, A , provided with retaining-flies A' , A^3 , and A^4 , a carbon sheet secured with said memorandum-paper under the retaining-fly A' , a memorandum-leaf secured under the flies A^3 and A^4 , and in connection therewith 35 elastic bands, wherewith said flies may be firmly held in place, substantially as described.

In testimony whereof I sign this specification in the presence of two witnesses.

JOHN H. FRINK.
